UNITED STATES PATENT OFFICE.

ANTON KOROPCZYK, OF NATRONA, PENNSYLVANIA.

FLUSH-TANK VALVE.

Application filed May 16, 1927. Serial No. 191,850.

The present invention is directed to improvements in flush tank valves.

The primary object of the invention is to provide a device of this character so constructed that the controlling valve will operate to close the discharge pipe without discharging the entire contents of the tank into the closet bowl.

Another object of the invention is to provide a device of this character so constructed that it can be easily and conveniently installed upon tanks already in use, the construction being extremely simple, and consequently can be manufactured at a very small cost.

With these and other objects in view, this invention resides in the novel features of construction, formation, combination and arrangement of parts to be hereinafter more fully described, claimed and illustrated in the accompanying drawing, in which,—

Figure 1 is a longitudinal sectional view through a flush tank, showing the same equipped with the device.

Figure 2 is a perspective view of the valve stem.

Figure 3 is a fragmentary detail view showing a modified form of the invention.

Referring to the drawing, 1 designates the flush water tank, 2 the discharge pipe, the upper end of which constitutes a seat for the float valve 3, all of which are of the usual construction. The pipe 2 as usual has connected thereto the overflow pipe 4, to which is secured an arm 5 having a guide 6 in which slides the stem 7, the lower end of which is secured to the valve 3, the upper end thereof being provided with an eye 7'. This stem has fixed thereto a weight 8, the purpose of which will be later explained.

Carried by the tank is a control handle having an arm 10 fixed thereto, to the inner end of which is pivoted the upper end of

the link 11, the lower end of said link being provided with an eye 12 for engagement with the stem 7. By providing the stem 7 with the weight 8 it will be obvious that as soon as the control handle is released the weight will cause the valve 3 to immediately seat upon the upper end of the pipe 2, and in this manner the amount of water discharged from the tank can be conveniently regulated.

In Figure 3 the stem 13 is formed from sections 14 and 15, the latter section having a weight 16 carried thereby and forming an integral part thereof for threaded engagement with the lower end of the section 14. In this manner the sections 14 and 15 can be readily disengaged, thus permitting the section 14 to be drawn through the eye 12 of the arm 11. Since the arm 5 is removable from the pipe 4, the section 15 can be lifted therewith, whereupon the section 15 can be slid through the guide 6 of the arm 65 upon removal of the valve 3. It will thus be seen that the stem section 14 can be removed without opening or distorting the eyes 7' and 12. The weight 16 not only serves its function but also provides a relatively large and strong connection between the sections 14 and 15.

Having thus described the invention, I claim:

The combination with a flush tank having a discharge pipe, a valve for controlling the discharge of water through said pipe, a stem for the valve consisting of upper and lower sections, a weight formed integral upon the upper end of the lower section, the upper section having its lower end threaded in the weight and aligned with the lower section, and means for operating the stem.

In testimony whereof I affix my signature.

ANTON KOROPCZYK. [L. S.]
